Primary Examiner — Sheryl Lane*Assistant Examiner* — Samantha N Wood(74) *Attorney, Agent, or Firm* — Weintraub Tobin; Zheng “Andy” Liu(57) **CLAIM**

The ornamental design for a robot, as shown and described.

DESCRIPTION

FIG. 1 is a front view of a robot;

FIG. 2 is a back view of the robot;

FIG. 3 is a left view of the robot;

FIG. 4 is a top view of the robot;

FIG. 5 is a bottom view of the robot; and,

FIG. 6 is a perspective view of the robot.

The right view is a mirror image of the left view.

The broken lines are included for the purpose of illustrating portions of the robot and form no part of the claimed design.

1 Claim, 6 Drawing Sheets(56)
